UNITED STATES PATENT OFFICE

2,194,330

FREEZING TRAY

Christian Steenstrup, Schenectady, N. Y., assignor to General Electric Company, a corporation of New York

Application February 1, 1939; Serial No. 254,059

8 Claims. (Cl. 62—108.5)

My invention relates to freezing trays for domestic refrigerators.

Freezing trays, as usually provided in refrigerating machines adapted for domestic use, are usually relatively shallow, rectangular metallic containers. In use, they are usually filled with water or other substance to be frozen and then placed on the surface of the cooling unit of the refrigerating machine in order to freeze the water contained therein. A partition assembly is commonly provided in freezing trays of this type in order to divide the tray into a number of small compartments so that the ice will be frozen in small blocks or cubes. In removing the ice cubes from the tray, the tray is usually placed in water in order to permit removal of the partition assembly and release of the cubes from the tray. Water is then passed over the exposed edges of the partition assembly and the cubes until the bond between the cubes and the partition assembly is broken and the cubes fall out or can be pressed out by the fingers of the users. Since water expands on freezing, in the conventional type of freezing tray a wedging action is produced against the grids, tray and the other cubes therein so that considerable water is necessary to free the cubes and frequently much of the cube is melted and therefore wasted.

Accordingly, it is an object of my invention to provide a new and improved arrangement for facilitating the removal of ice cubes from the freezing tray of a mechanical refrigerator of the domestic type which is simple and effective in operation and inexpensive to manufacture.

Further objects and advantages of my invention will become apparent as the following description proceeds and the features of novelty which characterize my invention will be pointed out with particularity in the claims annexed to and forming a part of this specification.

For a better understanding of my invention reference may be had to the accompanying drawing in which Fig. 1 is a perspective view of a freezing tray embodying my invention; Fig. 2 is an exploded view, partly in section, of the freezing tray and partition assembly shown in Fig. 1; and Fig. 3 is a view, partly in section, of the freezing tray illustrated in Fig. 1 as it appears when placed on the surface of a cooling unit or evaporator.

Referring to the drawing I have shown a freezing tray 10 of relatively shallow rectangular construction having a flat bottom wall 11 extending substantially throughout the length thereof. A partition assembly 13 including a longitudinal

partition element 14 and a plurality of transverse partition elements 15 is arranged within the freezing tray 10. The partition assembly illustrated herein is described and claimed in my U. S. Patent 2,067,799, assigned to the same assignee as the present application.

Adjacent one end of the freezing tray 10 an inclined bottom wall 16 is provided which extends across approximately half of the width of the freezing tray and provides an inclined bottom wall for the ice cube compartment formed by the partition assembly 13 adjacent one corner of the freezing tray 10. For example, as shown in Figs. 1 and 3, the ice cube compartment in the lower righthand corner of the freezing tray 10 is provided with the inclined bottom wall 16. In a similar manner, an inclined bottom wall 17 is provided for the ice cube compartment in the upper lefthand corner of the freezing tray 10. The liquid contained in the diagonally opposite corner compartments having the inclined bottom walls 16 and 17, respectively, will freeze subsequently to the freezing of the remainder of the ice cubes 18 due to the fact that the inclined bottom walls 16 and 17 do not lie in intimate contact with the freezing tray support or surface 19 of the cooling unit or evaporator 20 as does the flat bottom wall 11 of tray 10.

While I have described my invention as having inclined bottom walls associated with the diagonally opposite corner compartments only, it will be obvious that the inclined portions 16 and 17 of the bottom wall 11 of tray 10 may be of greater extent and any substantial portions 16 and 17 of the bottom wall may be so inclined as desired. The principal consideration is the area of the diagonally opposite portions of the bottom wall which are out of contact with the freezing surface rather than the size of the diagonally opposite end compartments because partition assemblies or dividers are dimensioned differently in the various constructions thereof whereby different sized cubes of ice are produced.

As shown in Fig. 2, side walls 21 of tray 10 are outwardly inclined as indicated at 21. As each cube freezes, a force acting between the partition element 14 and the side walls 21 will be produced. This force produces a shearing action on the partition assembly 13 and ice cube 18 since the cube, instead of being wedged between partition element 14 and the side walls of the ice tray 10 tends to move upwardly along the inclined side wall thereby facilitating removal of the cubes from the tray and from the partition assembly.

It will be apparent to those skilled in the art that modifications of the above-described exemplary arrangement are possible. For example, any arrangement whereby the liquid in the diagonally opposite corner portion of the tray is maintained out of direct heat transfer relationship with the freezing surface 19 may be substituted. Instead of providing inclined bottom walls 16 and 17 I may provide corresponding bottom walls extending above the plane of the major portion of the bottom wall and which may be horizontal or even curved, for example, with respect to the remainder of the bottom wall 11 and, accordingly, the surface 19 of the evaporator 20. Furthermore, if desired, a tray of conventional shape may be employed and blocks of relatively low heat conducting material may be inserted in the diagonally opposite corner compartments or the afore-mentioned corner compartments may be provided with partitions defining a dead air chamber which is interposed between the liquid to be frozen in the afore-mentioned corner compartments and the evaporator surface 19.

25 While I have shown a particular embodiment of my invention I do not desire my invention to be limited to the particular construction shown and described and I intend in the appended claims to cover all modifications within the spirit and scope of my invention.

What I claim as new and desire to secure by Letters Patent of the United States is:

1. A freezing tray having a partition assembly normally disposed therein to form ice cube compartments, the bottom wall adjacent one end of said tray having an inclined portion extending substantially half way across said tray, the bottom wall adjacent the other end of said tray having an inclined portion extending substantially across the other half of said tray.

40 2. A freezing tray having a partition assembly normally disposed therein to form ice cube compartments, the bottom wall of said tray associated with one corner compartment and the corner compartment diagonally opposite therefrom having substantial portions thereof inclined with respect to said bottom wall.

45 3. A freezing tray having a partition assembly normally disposed therein to form ice cube compartments, one corner compartment having an inclined bottom wall extending substantially across said corner compartment, the diagonally opposite corner compartment also having an in-

clined bottom wall extending substantially across said diagonally opposite corner compartment.

4. A freezing tray having a partition assembly normally disposed therein to form ice cube compartments, the bottom wall of said tray associated with one corner compartment and the corner compartment diagonally opposite therefrom having substantial portions thereof above the plane of the remaining portion of the bottom wall of said tray.

10 5. A freezing tray having a partition assembly normally disposed therein to form ice cube compartments, a substantial portion of the bottom wall adjacent one corner of said tray and also a substantial portion of said bottom wall adjacent the diagonally opposite corner of said tray being arranged above the remaining portion of said bottom wall of said tray.

15 6. The combination of a cooling unit and a freezing tray having a bottom wall in engagement with a surface of said cooling unit, said tray also having a partition assembly normally disposed therein to form ice cube compartments, a substantial portion of said bottom wall associated with a corner of said tray and also a substantial portion of said bottom wall associated with the diagonally opposite corner of said tray being arranged out of engagement with said surface of said cooling unit.

20 7. The combination of a cooling unit and a freezing tray having a bottom wall in engagement with a surface of said cooling unit, said tray also having a partition assembly normally disposed therein to form ice cube compartments, one corner compartment having a substantial portion of its bottom wall out of contact with said surface of said cooling unit, the diagonally opposite corner compartment also having a substantial portion of its bottom wall out of engagement with said surface of said cooling unit.

25 8. The combination of a cooling unit and a freezing tray having a bottom wall in engagement with a surface of said cooling unit, said tray also having a partition assembly normally disposed therein to form ice cube compartments, a substantial portion of said bottom wall associated with a corner of said tray and also a substantial portion of said bottom wall associated with the diagonally opposite corner of said tray being arranged out of engagement with said surface of said cooling unit, said tray also being provided with outwardly inclined side walls.
